(57) **CLAIM**

I claim the ornamental design for a filter for indoor barbecue, as shown.

DESCRIPTION

FIG. 1 is a top, perspective view of a filter for indoor barbecue with a filter unit in closed position showing my new design;

FIG. 2 is a right side view of the filter for indoor barbecue of FIG. 1;

FIG. 3 is a top view of the filter for indoor barbecue of FIG. 1;

FIG. 4 is a bottom view of the filter for indoor barbecue of FIG. 1;

FIG. 5 is a rear view of the filter for indoor barbecue of FIG. 1;

FIG. 6 is a front view of the filter for indoor barbecue of FIG. 1; and,

FIG. 7 is a perspective view of the filter for indoor barbecue of FIG. 1 showing the filter unit in open position.
